UNITED STATES PATENT OFFICE.

THOMAS COGHLAN AND WILLIAM LOISELLE, OF KANKAKEE, ILLINOIS.

MATTRESS-FILLER DEVICE.

Application filed August 10, 1927. Serial No. 211,904.

This invention relates to devices for filling or stuffing mattresses, cushions and the like.

The principal object of the invention is the provision of new and improved means for inserting padding in the pipes or compartments of mattresses, pads, cushions and like structures.

Another object of the invention is the provision of a device for inserting padding in mattresses and the like that is so constructed that the same will contain sufficient padding to fill a compartment or pipe of the mattress or cushion that is being filled.

A further object of the invention is the provision of a new and improved method of filling mattresses, cushions, pads and the like cheaply and expeditiously.

A still further object of the invention is the provision of a new and improved device for stuffing mattresses, pads, cushions and like structures that is so constructed that the padding will be inserted in a loose condition and will be evenly and smoothly distributed.

Another object of the invention is the provision of a new and improved device for filling or stuffing mattresses, cushions, pads and like devices that is cheap to manufacture, simple in construction, easily manipulated, efficient in operation, and that is not likely to become broken or get out of order.

Other and further objects and advantages of the invention will appear from the following description taken in connection with the accompanying drawings, in which:

Fig. 1 is a perspective view of the filler or pilot device with a load of padding therein;

Fig. 2 is a vertical section of a pad or mattress showing certain of the compartments with the padding in position therein, showing others empty, and still another with the invention in position therein; and

Fig. 3 is a cross section of the mattress or pad showing a load of padding in one of the compartments with the pilot device removed.

Referring now to the drawings, the numeral 10 designates what, for convenience, will be termed a mattress having the compartments 11 therein. These compartments extend transversely of the mattress, and are separated by flexible strips 12 in the usual manner.

Great difficulty heretofore has been experienced in inserting the padding or filling in the pipes or compartments 11. It is common practice to attach a strip of paper by

an adhesive to opposite sides of the padding to hold the same while it is being inserted in the compartments or pipes. This is objectionable, because it takes time and is more or less expensive. The present invention seeks to eliminate this difficulty, and provides means whereby the padding or filling may be readily inserted in the separate compartments.

Suitable means are provided for inserting the filler material within the compartments 11. As shown, a filler device 20 is employed for this purpose. It comprises a pilot member 13 and guard plates 14 and 15. The pilot member is formed from a strip of sheet metal bent to form what will be termed a box-like structure with open ends and having a bottom wall 16 and side walls 17. The free edges of said side walls may be and preferably are bent over toward each other to form retaining flanges 18, as clearly shown in Fig. 2 of the drawings. In order to strengthen the pilot member the flanges 18 may be return bent, as at 30, to form strengthening ribs. The pilot member is of proper dimensions to be readily inserted within the compartments 11, and is approximately the same length as said compartments.

One or more guard or retaining plates are provided for cooperating with the pilot member for inserting the filler material in the compartments, and for holding or retaining said material in said compartments while the pilot member is being withdrawn. As shown, two plates are employed for this purpose, an upper plate 14 and a lower plate 15. The plate 15 may be, and preferably is provided with an upturned portion at one end thereof, as at 21, which, when in position within the pilot member will constitute a closure for the inner end thereof. The upturned portion 21 is of such height as to be readily slidable beneath the flanges 18. The upturned end 21 constitutes a convenient means for manipulating said plate. The plate 14 is provided at one end intermediate the side edges thereof with an upstanding projection 22, which constitutes convenient means for manipulating the plate 14. The two plates 14 and 15 are slidable within the pilot member, as clearly indicated in Figs. 1 and 3 of the drawings. The pilot member 13 is provided with a handle 23, which may be, and preferably is rigidly attached to each of the side walls 17 on the outer side thereof.

The handle 23 is of less width than the height of the walls 17, so that the guard plate 14 may be slid in position from either end of the pilot member 13.

5 In loading the filler device the bottom guard plate 15 is placed in position in the pilot member 13, and the filler material, such as cotton, hair, or the like, is placed within the pilot member on the plate 15. The plate 10 14 is then slid from the inner end along the pilot member a short distance at a time, and the filler material is forced back under the plate 14 against the upstanding portion 21 as said plate is intermittently moved forwardly 15 until the pilot member 13 has been completely filled with the proper amount of filler material for one of the compartments or 20 pipes 11. When the pilot member is loaded, it is then inserted in one of the pipes or compartments 11. It is then withdrawn by the handle 23, the plates 14 and 15 remaining within the compartment for holding the filler material in position while said pilot is being removed. After the removal of the pilot 25 member the plates 14 and 15 may be removed one at a time by means of the upturned ends 21 and 22 without disturbing the filler material. The side edges of the filler material coming in contact with the side walls of the 30 compartments will hold the material from moving outwardly with the plates while they are being removed.

The filler member is approximately the same length as the mattress, so that when it is 35 inserted in the pipes or compartments and removed in sections, the filler material will be left in proper position within the mattress. When the pilot is removed, the resiliency of the filler material will cause it to expand, and 40 when the plates 14 and 15 have finally been removed, the material will expand to the desired thickness, as indicated in Fig. 2. It will be understood that the more filler material crowded or forced into the filler device 45 as it is being loaded, the thicker the cushion or mattress will be when the material is inserted in said compartments.

It is thought from the foregoing taken in connection with the accompanying drawings 50 that the construction and operation of our device will be apparent to those skilled in the art, and that various changes in size, shape, proportion and details of construction may

be made without departing from the spirit and scope of the appended claims. 55

We claim as our invention:

1. A device for inserting padding in mattresses and the like, comprising a long pilot member having bottom and side walls rigidly connected together, said member being open 60 at each end and having the outer portions of its side walls bent inwardly to form retaining flanges, a bottom guard plate for slidably engaging the bottom wall of said pilot member, and a removable guard member for engaging beneath said flanges whereby padding may be inserted in said pilot between said guard plate and member after said guard plate is in position in said pilot member. 65

2. In combination, a pilot member having bottom and side walls rigidly connected together and adapted to hold padding for a mattress, a guard member adapted to be slid into said pilot member and engage said bottom wall, a closure for said pilot member adapted to be positioned in said pilot member in spaced relation to said guard member for retaining said padding in position therein, and retaining members on said side walls for engaging said closure for preventing outward 75 movement of the same transversely to said pilot member. 80

3. In a device for filling mattress compartments, a pilot comprising a trough-shaped member for containing sufficient material to 85 properly fill one compartment, and an upper and a lower plate member for retaining said material within said compartment after the same has been inserted therein by said pilot while the latter is being removed, said members being removable from said compartment 90 after said pilot has been removed. 90

4. A device for filling mattress compartments comprising a long narrow trough-like structure open at each end, a bottom guard plate having an upturned end for constituting a closure for one end of said structure and 95 slidably on the bottom thereof, and a top guard plate slidably engaging the portion of said structure opposite said bottom guard 100 plate.

In testimony whereof we affix our signatures.

THOMAS COGHLAN.
WILLIAM LOISELLE.
